ADJUSTABLE HOLDER FOR DETACHABLE MOPS

Eugene J. Capstack, Louisville, Ky., assignor to
 Joseph E. Seagram & Sons, Inc., Shively, Ky.,
 a corporation of Indiana

Application October 21, 1946, Serial No. 704,701

6 Claims. (Cl. 15—150)

1

This invention relates to a mop holder.

Mop holders of many different types have been proposed in the past, the vast number thereof precluding a discussion of each. Each has apparently some advantages and disadvantages. Among the latter, a uniform and undesirable characteristic has been predominant, namely, that the actual mop-head engaging element is either secured to a handle, a hook or is otherwise formed so that it tends to entangle in the mop and prevent easy threading of the mop-engaging element with the mop. For instance in Patents 1,496,881 and 1,147,174 to Howenstein and Johnson, respectively, a locking handle is secured to the threading end of the mop engaging chain. In Patent 1,496,925 to Eddy, a handle is secured to one end of the mop engaging chain and a hook to the opposite end. In Patent 1,056,963 to Wing, the mop-engaging element is formed as a wire with a handle-engaging loop on one end. All such structures have been found disadvantageous in the removal and replacement of mop heads. The manner in which the strands of a mop can become entangled with its securing element in use by reason of the actual mopping and repeated rinsing, sterilizing and wringing is almost beyond human comprehension. Consequently, the removal problem is a considerable one because in large establishments the mops wear out in a relatively short time and must be replaced. It is also desirable that the mops be capable of being readily removed and replaced because of the desirability of washing them in mechanical washers.

In addition all such prior mop holders have been characterized by either relatively complicated locking means for one end of the chain or loop or complicated adjustment means for varying the lengths of the chain or loop in using mops of different sizes.

In overcoming the aforesaid disadvantages of the prior art, it is a major object of my invention to provide a novel mop holder of strikingly simple design wherein the mop-engaging element is formed of a single, flexible element of substantially constant cross-section and arranged so that a free end thereof without any hooks or the like is provided for threading through the mop.

Another object of my invention is the provision of a novel mop head wherein a flexible element such as a chain is provided for engaging the mop, the chain being adjustable in length to a degree much less than the length of the individual links of the chain.

A further object of my invention is the provision of a novel mop head characterized by its ease

of securement to and release from a mop, and its design whereby all the mop-engaging and locking elements are fixed to the holder and cannot be and need not be removed therefrom in removing or replacing a mop.

Other objects and advantages of my invention will be apparent from the following description and claims taken with the attached drawings, wherein:

10 Fig. 1 is an elevation of a preferred embodiment of my invention in a position where a mop is being attached thereto.

Fig. 2 is a detail in perspective illustrating the manner in which the handle is mounted at one end of the base member and locked thereon.

Fig. 3 is a detail in perspective of the opposite end of the base member illustrating the manner in which the free end of the mop-engaging chain is secured.

Fig. 4 is a perspective of the mop holder in locked position, the mop being omitted to more clearly show the elements of the holder.

In the preferred embodiment illustrated herein, a base member 11 of generally arcuate shape, approximating a triangle, and formed in part as an outwardly facing channel, is secured as by a pin 12 to a handle-receiving socket 13, the end of the socket being preferably secured to the base member at the mid-point of its center leg by a pin 14.

A chain tightener of the self-locking type comprises a handle 15 pivoted at 16 to the opposed legs of a bracket 17 secured to one side leg of the base member as by a pin or rivet 18. The pivoted end of the handle is formed as a U, thus permitting one end of a flexible chain 19 or like element to be received therein while secured to a pin 21. Because in locked position the chain 19 passes through the U-shaped end of the handle 15 between the pivot 16 and the base member 11 past dead center, its pull or force vector upon handle 15 will be in a direction having a clockwise component as seen in Figure 4, thus holding the handle against the base member to provide

45 a self-locking or toggle action. The chain will exert a pull upon the handle, holding it locked against the base member until the handle is manually rotated clockwise as seen in Figure 1, past dead center to bring the pull of the chain exterior 50 of the pivot 16, whereupon the pull of the chain will tend to open the handle. It will be noted that the handle and the chain attached thereto are permanently secured to the base member and need not be removed therefrom in removing or

55 replacing the mop. It will also be noted that in

its self-locking position as shown in Fig. 4, the handle 15 is shaped to conform to the adjacent portions of the base member and the handle, thereby eliminating any possible interference in the use and wringing of the mop.

The leg of the base member opposite the handle leg is formed with a slot 22 and a series of spaced apertures 23, the latter being spaced apart a distance less than the length of a link of the chain and preferably a distance equal to about one-half the length of a chain link. A connector or anchor member 24 is fixed in slot 22 in a manner to be adjusted therealong but not removable therefrom by a pin or rivet 25 having a head 26 larger than the diameter of the slot. The opposite end of the connector carries a pin having a section 28 arranged to engage apertures 23 and another section 29, preferably bent as shown in Fig. 3, to engage any link of chain 19. In lieu of the pin, appropriate lugs can be stamped from connector 24 to engage apertures 23 and the chain links.

When a mop is to be attached to the holder, the handle is moved to full open position i. e., clockwise of the position of Fig. 1 and the free end of chain 19 threaded through the mop. The mop may be of the type shown at 31 having a pocket 32 secured thereon or may be of the more conventional type consisting of loose strands secured at their midpoints by a canvas strip. Both types raise equal problems as regards entanglement.

After pulling chain 19 through the mop, the free end thereof is secured to pin 29, the link selected being such as to properly adjust the effective length of the chain, this being determined by moving the handle to locking position. If the desired adjustment cannot be secured within the limits of the length of a link on the chain, connector 24 may be lifted and adjusted to place pin 28 in a different aperture 23, thus changing the adjustment about one-half link. Assuming that the chain has now been correctly adjusted, handle 15 may be moved to the position of Fig. 4. It will be noted that in adjusting the position of connector 24 and correspondingly changing the effective length of the chain, it is not necessary to disconnect the chain therefrom.

When the mop is to be taken off the holder, handle 15 is unlocked and the free end of the chain removed from pin 29. A single shaking of the holder will then free the mop since the end of chain 19 is free of a hook or any element that might entangle in the mop.

The mop holder of this invention has proven highly satisfactory in use and particularly efficient as regards the quick-change of mops thereon. By reason of the manner in which the mop is arranged and secured to the holder, the holder is fully protected in use.

Having described my invention, I claim:

1. A mop holder comprising: a base member having a channel portion and having a longitudinal slot and a longitudinal series of apertures therein; an anchor member having a portion

permanently received in said slot for sliding engagement, and a portion receivable in a selected aperture for holding said anchor in adjusted position; a flexible mop clamping member providing at least one loop therein; a hook on said anchor to removably receive a loop in said clamping member; and a tightener secured to said base member and anchoring the opposite end of the flexible member.

10. 2. A mop holder comprising: a base member having a channel portion and having a longitudinal slot and a longitudinal series of apertures therein; an anchor member having a portion permanently received in said slot for sliding engagement, and a portion receivable in a selected aperture for holding said anchor in adjusted position; a chain for clamping a mop member; a hook on said anchor to removably receive a link in said chain; and a tightener secured to said base member and anchoring the opposite end of said chain.

15. 3. A mop holder as specified in claim 2 wherein said apertures are spaced apart less than the length of a chain link.

20. 4. A mop holder comprising: a base member having a channel portion and having a longitudinal slot and a longitudinal series of circular apertures therein; an anchor strip having a headed pin permanently received in said slot for sliding engagement, and a dowel receivable in a selected aperture for holding said anchor in adjusted position; a flexible mop clamping member providing at least one loop therein; a hook on said anchor strip to removably receive a loop in said clamping member; and a tightener secured to said base member and anchoring the opposite end of the flexible member.

25. 5. A mop holder as specified in claim 4 wherein said flexible mop clamping member is a chain, and said circular apertures are spaced apart less than the length of a chain link.

30. 6. A mop holder as specified in claim 1 wherein said tightener has a pair of prongs at its end independently pivoted to the channel portion to provide an opening between the prongs, the flexible clamping member passing between the prongs in clamped position and being fastened to the tightener intermediate the ends thereof to hold the tightener by a toggle action.
